BELT DRIVEN PARKING METER

Herman S. Johns, Oklahoma City, Okla., assignor
to Dual Parking Meter Company, Oklahoma
City, Okla., a corporation of Delaware

Application December 6, 1935, Serial No. 53,191

8 Claims. (Cl. 194—1)

My invention relates to meters, and more particularly to coin operated time measuring meters for collecting for vehicle parking and the like.

The prime object of the present invention is to provide a device of this class which is simple in construction, may be cheaply manufactured, and utilizes a coin for the purpose of indicating elapsed and unelapsed parking time.

Other objects of the invention are to provide a device of the class described which is new, novel, practical and of utility; which has fewer moving parts than other devices previously designed for such purpose; which utilizes the coin as a means for readily indicating whether or not the parking space being used is paid for; which may be easily and quickly adjusted for various periods of parking time; which displays the coin after insertion so as to prevent the use of a slug; a device in which the coin operates no mechanism, but merely acts as an indicator along a stationary time scale; which is durable; and, which will be efficient in accomplishing all purposes for which it is intended.

With these and other objects in view as will more fully appear hereinbelow, my invention consists in the construction, novel features, and combination of parts hereinafter more fully described, pointed out in the claims hereto appended, and illustrated in the accompanying one-sheet drawing, of which,

Figure 1 is an elevational view of the device, the upper part being in section and showing the coin conveying mechanism in operative position;

Figure 2 is a sectional view taken substantially along the line 2—2 of Fig. 1;

Figure 3 is a perspective view of the device installed on the top of a hollow post, in operative position; and,

Figure 4 is a perspective fragmentary view of the coin conveying belt.

Like characters of reference designate like parts in all the figures.

It is understood that various changes in the form, proportion, size, shape, weight, material and other details of construction, within the scope of my invention may be resorted to without departing from the spirit or broad principle of my invention and without sacrificing any of the advantages thereof; and it is also understood that the drawing is to be interpreted as being illustrative and not restrictive.

The inventive idea involved is capable of receiving a variety of mechanical expressions one of which, for the purpose of illustrating the in-

vention, is shown in the accompanying drawing wherein:

The reference numeral 1 indicates a head, made integral with a hollow cylindrical base member 2, adapted to lock in stationary position over the top of a post 3, by means of an ordinary locking element 4. The head is divided by a coin passage 5 formed by two aligned transparent windows 6 in connection with the walls of the head 1. The passage 5 communicates 10 at one end with coin slots 7 and at its other end with a coin receptacle (not shown) supported by the base member 2. The passage 5 also communicates throughout its length with a suitably shaped space or housing 8 located in the wall 15 of the head 1. The windows 6 are spaced apart sufficiently to barely permit the passage of a coin slug, token or their mechanical equivalent 9 through the passage 5. The housing 8 also communicates with the hollow cylindrical base 2, 20 and serves as a housing for a mechanical conveying unit, which will now be described.

Two metal plates 10, their side surfaces oppositely disposed and aligned, are spaced apart by and made integral with two interior oppositely disposed and aligned metal walls 11, of a shorter length than the outside plates. Both ends of the walls 11 are turned inward toward each other as shown at 12, and serve as an inner guide for a belt 14.

Beyond the ends of the walls 11 and between the inner surfaces of the ends of the plates 10, are axially mounted two belt pulleys, as shown at 13. Mounted over these two pulleys is the endless soft rubber belt 14, the inner surface of which is protected from wear by a slightly wider and stiffer material 15, such as leather or the like, made integral with the soft rubber portion. One of the two pulleys in the driving unit is adapted to be driven to rotation by a power means (not shown), 40 which is preferably housed in the base 2 or the post 3. The complete conveying unit is inserted into the housing 8 of the head 1, and is held in position by screws through perforations (not shown) in one of the plates, and into corresponding screw holes (not shown) in the wall of the head 1. In operating position the outer surface of the belt 14 is in communication with the coin passage 5, and is so spaced from the opposite coin passage wall that the edge of a 50 coin of the correct denomination will contact both the wall opposite the belt and the surface of the belt, and cannot pass along the passage 5, without propulsion by the belt.

In operation, the device may be located in a 55

limited parking zone. A coin 9 is inserted by a customer in one of the coin slots 7, passes into the passage 5, where its opposite edges contact the wall of the passage, and the surface of the belt 14. The surface of the belt is sufficiently soft to slightly grip frictionally the edge of the coin, and by this contact, to move the coin along the passage. The belt is in constant movement around the pulleys, and since the coin moves through the passage at exactly the speed of the belt, the speed of the coin through the transparent passage 5 may be regulated by a speed ratio change in the power transmitting mechanism.

If placed in a fifteen minute parking zone, the speed is regulated so that the coin is visible from either side of the passage 5 for a total period of only fifteen minutes. Likewise, if the device is placed in an hour parking zone the speed of the belt is regulated so that the coin is visible in the passage for a total of one hour. When the coin has passed half way through the passage, an observer can easily tell that half of the parking time has elapsed, and can easily estimate the number of minutes unelapsed, depending on the time zone in which the car is parked. When the entire parking time has elapsed, the coin has reached the end of the passage 5, and is released from contact with the surface of the belt 14, and drops from view into a coin receptacle (not shown) located in the base member 2.

Periodically the head 1 and base member 2 are unlocked from their position over the post 3, the coins are removed from the receptacle, and the device replaced and locked in its operating position.

Obviously, the invention is susceptible of embodiment in forms other than that which is illustrated in the accompanying drawing and described herein, and applicable for uses and purposes other than as detailed, and I therefore consider as my own all such modifications and adaptations and other uses of the form of the device herein described as fairly fall within the scope of my invention.

Having thus described my invention, what is claimed and desired to be secured by Letters Patent, is:

1. In a device of the class described, a coin receiving passage having oppositely disposed transparent walls, and a resilient endless conveyor belt driven at a uniform speed along the passage and adapted to frictionally engage the edge of a coin in the passage for causing its movement along the passage.

2. In a device of the class described, a housing comprising a hollow head and a hollow base, a pulley axially mounted at the lower end of said head, a pulley axially mounted at the upper end of said head, a resilient endless belt driven to travel over said pulleys, a coin passage adjacent to and open at one edge to communicate with a portion of said belt, one wall of said passage, together with said portion of the belt, so spaced apart as to engage simultaneously the edge of a coin in the passage, the belt adapted to roll the coin along the passage as the belt moves over the pulleys.

3. In a device of the class described, a coin receiving passage having two opposite trans-

parent walls, and a sponge rubber conveyor belt extending and driven to travel along one edge of said passage, said belt adapted to engage a coin in the passage and control its movement along said passage.

4. In a device of the class described, a coin receiving passage having two oppositely disposed visible transparent parallel walls, and a resilient endless conveyor belt forming one edge of said passage, the opposite edge being so spaced from said belt that the edge of a coin of certain diameter in the passage would be contacted both by the belt and the opposite edge of said passage, said belt adapted to be driven at a uniform speed along the passage, thereby causing a coin to move along the passage at the same speed as the belt, a coin in the passage adapted to visibly divide the passage during its propulsion by the belt, and thereby indicate the elapsed and unelapsed proportion of the total time necessary for the coin to pass from one end of the passage to the other end.

5. In a device of the class described, a coin receiving passage having two oppositely disposed transparent walls, a resilient endless belt forming one edge of said passage, a power driven pulley adapted to drive said belt at a constant speed along said passage, said belt adapted to engage the edge of a coin in said passage, to cause its contact with the opposite edge of said passage, and to propel the coin along the passage at a predetermined speed, and means for limiting lateral movement of the belt in a direction away from the coin.

6. The combination with a pulley driven at a predetermined speed, of a second pulley spaced from the first, and a resilient endless belt over said pulleys, the belt extending along the edge and forming one wall of a coin receiving transparent sided passage, and adapted to propel a coin therethrough, the coin adapted to visibly divide the length of the passage during its travel from one end of the passage to the other.

7. In a device of the class described, the combination with a housing and a coin receiving passage therein formed with oppositely disposed transparent side walls, and having one open edge, of means for controllably conveying a coin along the passage including: a driving pulley and a driven pulley, means for rotatably mounting the pulleys in spaced relation, and a resilient endless conveyor belt operably mounted on the pulleys, said pulleys, mounting means, and belt adapted to be removably disposed as a single unit along the open edge of said passage with the belt in position to contact the edge of a coin in the passage and convey it along the passage.

8. In a device of the class described, a coin passage including two opposite transparent side walls, a solid edge wall, and an opposite edge wall in the form of a resilient endless movably mounted belt; means for moving the belt along the passage at a uniform speed; the two edge walls adapted to receive and cooperatively hold between them, by contacting its edge at opposite points, a coin of predetermined size; the said resilient belt adapted, as it moves, to roll the coin along the opposite edge wall and along the passage.

HERMAN S. JOHNS.
